REVERSIBLE SELF-CLEANING RADIATOR

Albert M. Middleton, East Lansdowne, Pa.

Application December 6, 1938, Serial No. 244,266

3 Claims. (Cl. 257—129)

The present invention relates to new and improved radiators and more particularly to such devices constructed in a manner to be reversed on a vehicle to change the flow of water therethrough.

As is well known, foreign substance in a radiator caused by rust, scale and particles of oil from the motor, usually settles on top of the radiator core and very seldom penetrates into the cellular structure and, due to the continual circulation of water in one direction, such foreign substances will become permanently embedded in the core. Over a period of time this condition usually results in overheating of the radiator caused by faulty circulation of the water and oftentimes the radiator will leak as a result thereof. The herein described radiator being reversible and readily removable for reversing will greatly improve the above conditions. Reversing the position of the radiator places the clogged top of the core to the bottom and changes the flow of water which, through assistance of the water pump, forces out any obstruction that has a tendency to accumulate and settle in the core. Also, a periodic reversing of the core will, to a large extent, minimize the accumulation of foreign substance therein.

It is, therefore, the primary object of the invention to provide a radiator for use with an oil or gasoline water cooled motor that is readily reversible whereby the direction of flow of water therethrough can be changed to prevent partial obstruction of the core of the radiator.

A still further object of the invention is to provide a reversible radiator including baffled tanks with extra hose and filler connections which when not in use, are capped by novel means forming part of the invention.

The invention will be fully and comprehensively understood from a consideration of the following detailed description when read in connection with the accompanying drawing which forms a part of the application.

In the drawing—

Figure 1 is a front elevational view with parts in section of a radiator constructed in accordance with the present invention.

Figure 2 is a side elevational view of the radiator with the lower part in section, and

Figure 3 is a top plan view of the radiator disclosed in Figure 1.

Referring to the drawing for a more detailed description thereof, wherein there is illustrated the preferred embodiment of the invention, the new and improved reversible type radiator is

indicated generally by the reference numeral 5 and includes top and bottom sections 6 and 7 respectively of identical forms. The sections 6 and 7 include header tanks 8 and 9 respectively, each tank being formed with a baffle plate 10 5 more clearly illustrated in Figure 2 of the drawing, said tanks communicating with the cellular structure of the radiator core 11 in the conventional and well known manner.

The top section 6 further includes a filler 10 connection 12 extending therefrom and closed by a suitable cap 13, said cap being attached to the section by means of a chain or the like 14. The bottom section 7 is likewise formed with a filler connection 15 and cap 16 attached to the section 15 by means of the chain or the like 17.

Each filler connection 12 and 15, respectively, has attached thereto by any desired means, overflow pipes 18 and 19, respectively, each pipe carrying a pet cock valve 20 and 21 respectively, one 20 of which is adapted to be shut off when not in operation. In other words, when the radiator is in the position illustrated in Figure 1 of the drawing, the overflow pipe 19 is not in operation and consequently the pet cock 21 remains closed, 25 with the pet cock 20 and its associated pipe in operation and therefore open.

Inlet and outlet connections are formed on each of the sections 6 and 7 one of which is adapted to be closed by an expansible plug when 30 not in use. In Figure 1 of the drawing, the top section 6 is illustrated with an inlet connection 22 supporting thereon a rubber hose 23, and an outlet connection 24 closed by the expansible 35 plug 25. The position of the inlet and outlet 35 connections on the bottom section 7 is substantially reversed to that used in the top section 6. On the bottom section 7 the outlet connection 26 supports the rubber hose 28 and the inlet connection 27 is closed by the expansible plug 28'. Referring to Figure 2 of the drawing, there is more clearly illustrated the type of expansible 40 plug used for closing the connections not in use, said plug comprising an expansible cylindrical member 29 formed of rubber or similar 45 material and having extending therethrough a threaded bolt 30. A metallic washer 31 is carried by the bolt and is held in associated relation with the member 29 by means of the wing nut 32. As illustrated, the metallic disk is substantially 50 greater in diameter than the connection with which it is used, and after insertion of the expansible member 29 within the connection, the wing nut 32 is tightened thereby causing the member 29 to expand within the connection and 55

become wedged therein. Thus a tight leakproof plug is provided for the unused connections.

For attaching the radiator to the vehicle in a manner to be readily detached therefrom, there is provided a pair of L-shaped brackets 33 and 34 supported on the side walls of one end of the radiator and a similar pair of brackets 35 and 36 on the other end of the radiator. The brackets are formed with openings for receiving the connecting members 37 for bolting the radiator to the frame 38 of the vehicle.

When desiring to reverse the position of the radiator from that illustrated in the drawing the bolts 37 and hose connections 23 and 28 are removed. The reverse end of the radiator is then attached by means of the bolts and brackets 33 and 34 and hose connections substituted for the expandible plugs 25 and 28'. The expandible plugs are then positioned in the connections 22 and 26. Thus connection 27 will become the inlet and connection 24 the outlet for the radiator in its reversed position so that the flow of water through the radiator will be reversed. Naturally, when reversing the radiator the rust and scale that was formerly on the top of the core will be on the bottom thereof so that the reversing of the flow of water through the radiator will force the rust and scale from the core and it being of a metallic substance that is heavier than water will sink to the bottom of the tank and lodge in the filler neck 15. In other words, a trap will be formed in the bottom-most portion of the radiator below the outlet connection and the dislodged rust and scale can be periodically removed from the filler neck.

It is to be noted that the filler caps are formed with a washer 39 best shown in Figures 1 and 2 of the drawing whereby a leakproof connection is provided to prevent loss of water through the bottom section.

Also it will be understood, of course, by those skilled in the art that variations in the hereinabove described device involving the substitution

of substantial equivalents for the devices described are intended to be comprehended within the spirit of the present invention and that the invention is capable of extended application and is not confined to the exact showing of the drawing nor to the precise construction described and, therefore, such changes and modifications may be made therein as do not affect the spirit of the invention nor exceed the scope thereof as expressed in the appended claims. 10

What is claimed as new is:

1. An automobile radiator comprising, a casing having top and bottom header tanks, a core supported between said tanks and in communication therewith, means for removably attaching said radiator to an automobile for reversing the position thereof, and a plurality of connections associated with said tanks adapted to permit circulation of water through said core. 15

2. An automobile radiator comprising, a casing 20 having spaced top and bottom header tanks, a core supported between said tanks and in communication therewith, a filler connection extending from substantially the central portion of each tank, a plurality of connections extending from the rear walls of said tanks adapted to permit circulation of water from a motor through said core, and means for removably attaching said radiator to said automobile for reversing the position thereof. 25

3. An automobile radiator comprising, a casing having top and bottom sections, each section formed with a header tank therein, a core supported between said sections and in communication with said tanks, filler connections extending substantially centrally of said sections, outlet members extending from the rear walls of said sections adapted to receive a hose for connection with a motor to permit circulation of water from said motor through said core, and means for removably attaching said radiator to the automobile for reversing the position thereof. 35 40
